(57) **CLAIM**

We claim the ornamental design for a spray cap, as shown and described.

DESCRIPTION

FIG. 1 depicts a perspective view of a spray cap.

FIG. 2 depicts a front elevation view of a spray cap.

FIG. 3 depicts a rear elevation view of a spray cap

FIG. 4 depicts a side elevation view of a spray cap.

FIG. 5 depicts an opposite side elevation view of a spray cap.

FIG. 6 depicts a top plan view of a spray cap; and,

FIG. 7 depicts a bottom plan view of a spray cap.

The broken lines in the drawings illustrate environmental structure on the article and form no part of the claimed design.
